(57) **CLAIM**

The ornamental design for a canopy with anchor, as shown and described.

DESCRIPTION

FIG. 1 is a front perspective view of a canopy with anchor according to our new design;

FIG. 2 is a front side elevational view thereof, of which the back side elevational view is a mirror image;

FIG. 3 is a right side elevational view thereof, of which the left side elevational view is a mirror image;

FIG. 4 is a top plan view thereof; and,

FIG. 5 is a bottom plan view thereof.

The broken lines are for the purpose of illustrating portions of the article that form no part of the claim.
